THREAD CONTROL MECHANISM FOR
SEWING MACHINES

Leo Schwartz, New York, N. Y.

Application July 8, 1950, Serial No. 172,657

2 Claims. (Cl. 112—219)

1

The present invention is directed to a control mechanism for sewing machines, more particularly to a device which operates so that when a thread breaks, the machine is automatically stopped.

In the needle industries, high speed sewing machines are used for quantity production. Such machines run at speeds of 3000 or 4000 R. P. M. or even higher. Therefore, the production of garments is at a high rate since the fabric runs through the machine at a high speed. However, when the thread breaks or a bobbin becomes exhausted, the machine continues to feed the fabric without completing the sewing. In a few seconds a considerable amount of fabric may thus pass through the machine before the machine can be stopped manually. This necessitated removing the fabric from the machine and pulling it back to a position where the stitching had ended. Such procedure wasted considerable time and it interfered with the productivity of the machine and operator. To overcome these disadvantages, it has been proposed to provide automatic means for stopping a sewing machine when the thread breaks. Among such devices were mechanical arrangements which were actuated by the breaking of a thread to cause mechanical movements to take place, disconnecting the machine from the driving means, or stopping a motor or the like. Such expedients were not fully effective for the desired purpose since they did not operate instantaneously but required several seconds for operation so that it did not stop the machine immediately upon the breaking of a thread.

The present invention is intended and adapted to overcome the difficulties and disadvantages inherent in prior devices of the type described, it being among the objects of the present invention to provide a control device for stopping a sewing machine which is set into action by the breaking of a thread.

It is also among the objects of the present invention to provide a device which is highly sensitive and which operates instantaneously upon the breaking of a thread to electrically stop the operation of the machine.

It is further among the objects of the present invention to provide a device of the character described, which is simple in construction, positive in operation and which may be subjected to use on high speed machines for long periods of time without deterioration.

In practicing the present invention there is provided an element which is suitably mounted and usually on the arm or head of a sewing machine. It includes a plunger mounted for longitudinal movement and having an eye at one end thereof through which a thread is passed from a spool to the needle of the machine. A coil spring surrounds a portion of the plunger and is so arranged that it tends to retract the plunger against the

2

tension of the threads. At the other end of the plunger is a contact which is adapted to be moved into operative relation with a fixed contact whereby an electrical circuit is formed. This occurs upon the breaking of a thread whereby the action of the spring causes closing of said contacts or switch.

There is further provided a solenoid having an armature, the solenoid being in the circuit with the aforesaid switch. A latch arrangement is provided to hold a catch in a certain position, allowing operation of the machine. Upon actuation of the solenoid, the catch is released, causing a shaft to be oscillated and a clutch to be disengaged. By such an arrangement, within a fraction of a second of the breaking of a thread, the machine can be stopped.

In the accompanying drawing constituting a part hereof and in which like reference characters indicate like parts,

Fig. 1 is a perspective view of the head and arm of a sewing machine, showing the switching arrangement in position relative to the thread and needle;

Fig. 2 is a longitudinal cross-sectional view taken through the switching device;

Fig. 3 is a top plan view of the stop mechanism, some parts being removed for clearness;

Fig. 4 is a view similar to Fig. 3, showing only the left-hand portion with the elements in a different position, and

Fig. 5 is a transverse cross-sectional view taken along the line 5—5 of Fig. 3.

There is provided the usual arm 1 and head 2 of a sewing machine containing the ordinary sewing instrumentalities and having in this case a pair of needles 3. The device is applicable to a single needle machine as well as a multiple needle machine. A pair of thread tensions 4 carry threads 5 through a suitable eye 5' and then in operative relation with element 6 which is attached to arm 1 by strap 7 and suitable screws or bolts. The thread passes through eye 8, tension 9, loop 10, and to the needles.

Casing 6 has a pair of longitudinal openings 11 and 12 therein, carrying plungers 13 and 14, respectively. A pair of spaced bearings 15 and 15' is provided for plunger 13 and a similar pair of spaced bearings 16 and 16' are provided for plunger 14. Blocks 17 and 18 are fixed on plungers 13 and 14, respectively, and coil springs 19 and 20 surround said plungers, bearing against the blocks at one end and bearings 15' and 16' at the other end.

The plungers are provided with eyes 21 and 22, respectively, through which threads 5 are adapted to pass. At the opposite end of casing 6 are insulating elements 23 fixed to said casing and having a conducting plate 24 on the outer end thereof. A terminal 25 is secured to plate 24 to accommodate a wire 26. Plungers 13 and 14

have at their left hand ends heads 27 and 28, respectively, carrying contact members 27' and 28'. Corresponding fixed contact members 29 and 30, respectively, are provided on the inside of plate 24 adjacent to heads 27 and 28.

Plate 31 is secured to the end of casing 6 adjacent to eyes 21 and 22. Arms 32 and 33 extend at approximately right angles to plate 31 and have openings 34 and 35 in the ends thereof. Threads 5 are adapted to pass through openings 35, then through eyes 21 and 22, through openings 34 and then to the needles, as shown in Fig. 1.

The actuating mechanism for the stop mechanism consists of a casing 36 open on one side and adapted to be closed by cover 37 and set screws 38.

An operating handle 39 is secured to one end of shaft 40, passing through casing 36. The other end of handle 39 is suitably secured to a clutch or other element whereby on oscillation of said shaft, the clutch is disengaged, or any other usual element is moved to stop operation of the machine.

Block 41 is fixed on shaft 40 and coil spring 42 is secured to the block and the casing at its ends so as to normally bias shaft 40 in the direction of the arrow. A solenoid 43 has armature 44 mounted therein for longitudinal movement. Block 45 is secured thereto and retains coil spring 46 surrounding it and normally biasing the armature in the direction of the arrow. Pin 47 extending into casing 36 is in contact with the end of armature 44 and may be used manually for retracting said armature by pressing on the head of said pin.

An arm 48 is fixed on shaft 40. Pivoted at 49 to armature 44 is latch 50 mounted on pin 51 for oscillation. Latch 50 has a recess 52 therein for the reception of catch 53 mounted on arm 48. Stop 54 limits the oscillation of shaft 40 by contacting with arm 48.

Said arm carries contact member 55 adapted to close a circuit with a complementary contact member on the end of resilient blade 56 which is secured to insulating block 57, the latter being mounted in casing 36. Blade 58 on the opposite side of member 57 is electrically connected therewith and has a wire 59 attached to one of the terminals of solenoid 43. Wire 26 is attached to terminal 60 which is the other terminal of the solenoid.

In the operation of the device, the elements are in the position shown in Figs. 1 and 3 and the plungers are in the position of plunger 13 in Fig. 2. The solenoid circuit is broken. When a thread breaks as shown in Fig. 2 by the position of plunger 14, the tension having been released and spring 20 causing contacts 28 and 30 to close, current flows through wire 26 and the other elements of the circuit including solenoid 43. This retracts armature 44, oscillating latch 50 to the right as shown in Fig. 4, releasing arm 48 and catch 53. This allows spring 42 to twist shaft 40 in the direction of the arrow until arm 48 contacts stop 54. The twisting action causes operation of a clutch or other element to stop the machine.

In order to start the machine after the needle is rethreaded, handle 39 is pressed so as to twist shaft 40 in a direction opposite to the arrow, thus allowing arm 48 and catch 53 to move into locking position, as shown in Fig. 3. If during the operation of the machine the operator desires to stop it, he merely presses pin 47, causing armature 44 to be retracted, arm 48 to move upwardly, breaking a circuit of contacts 55-56.

Although the invention has been described setting forth a single specific embodiment thereof, various changes in the details of construction may be made within the principles herein set forth. For instance, casing 6 need not be of rectangular form but may be of any suitable shape. It may be mounted on the head of the machine or adjacent to the needles and fixed to the bed or other stationary part. The plungers and associated elements may be of different form and they need not be parallel to each other.

These and other changes may be made within the spirit of the invention, which is to be broadly construed and not to be limited except by the character of the claims appended hereto.

I claim:

1. In a thread control mechanism for a sewing machine comprising a hollow casing adapted to be attached to said machine, at least one plunger mounted in said casing for longitudinal movement therein and extending out of one end thereof, an electrical contact on the portion of said plunger within said casing, an eye on the extending end of said plunger and through which a tensioned thread is adapted to pass, a fixed electrical contact in said casing in cooperative relation with said plunger contact, resilient means in said casing and surrounding said plunger biasing said plunger towards said fixed contact against the tension of said thread, the improvement which includes a solenoid having an electrical connection to said fixed contact, an armature longitudinally movable in said solenoid, a latch pivoted on said armature, a shaft adjacent to said armature and having an arm secured thereto, said arm carrying a catch, said latch having a recess cooperating with said catch, said catch adapted to enter said latch.

2. In a thread control mechanism for a sewing machine comprising a hollow casing adapted to be attached to said machine, at least one plunger mounted in said casing for longitudinal movement therein and extending out of one end thereof, an electrical contact on the portion of said plunger within said casing, an eye on the extending end of said plunger and through which a tensioned thread is adapted to pass, a fixed electrical contact in said casing in cooperative relation with said plunger contact, resilient means in said casing and surrounding said plunger biasing said plunger towards said fixed contact against the tension of said thread, the improvement which includes a solenoid having an electrical connection to said fixed contact, an armature longitudinally movable in said solenoid, a latch pivoted on said armature, a shaft adjacent to said armature and having an arm secured thereto, said arm carrying a catch, said latch having a recess cooperating with said catch, said catch adapted to enter said latch, a spring surrounding said shaft tending to twist said shaft to maintain said latch and catch out of engagement.
